3 Claims. (Cl. 315—11)

1

This invention relates to electron discharge devices, such as television transmission tubes which are used for converting an image of an object into signals for television transmission.

In such devices a target electrode is employed, elemental areas of which are capable of acquiring varying potentials when an optical or electron image is projected on to said electrode, said elemental areas being restored successively to an equilibrium potential by scanning with an electron beam. Usually the arrangement is such that elemental areas of the target electrode are charged positively in proportion to the brightness of the elemental areas of the object for transmission and the target electrode is scanned in one type of television transmission tube with a high velocity beam which restores the elemental areas to an equilibrium potential corresponding substantially to that of the anode of the tube. In a television transmission tube of this type, undesirable signals referred to as background and shading are liable to arise since the discharge of the elemental areas of the target electrode is accompanied by secondary electron emission from the target electrode, the undesirable signals being due principally to variations in the secondary emission over the target electrode surface.

The object of the present invention is to provide an improved electron discharge device such as a television transmission tube, with a view to eliminating or substantially reducing the undesirable signals referred to.

According to the present invention there is provided an electron discharge device comprising a target electrode, means whereby a negative charge image can be formed on said target electrode, means for scanning said target electrode with an electron beam whereby secondary electrons can be released from said target electrode, and means for removing secondary electrons released from said target electrode, the arrangement being such that the number of secondary electrons removed from more negatively charged areas of said target electrode is greater than from less negatively charged areas of said target electrode.

According to the present invention there is also provided a circuit arrangement comprising an electron discharge device incorporating a target electrode, means for forming a negative charge image on said target electrode, means for scanning said target electrode with an electron beam at a velocity sufficient to release secondary electrons from said target electrode, means for re-

2

moving secondary electrons from said target electrode, the arrangement being such that the number of secondary electrons removed from more negatively charged areas of said target electrode is greater than from less negatively charged areas of said target electrode, and means for generating electrical signals representative of said charge image.

If as has been proposed, in television transmission tubes such as referred to in the second paragraph of the specification, the secondary electrons are utilised for generating picture signals, as by directing them to an electron multiplier, the number of secondary electrons which can be so utilised is greater from areas of the target electrode corresponding to dark areas than from bright areas so that the noise tends to be a maximum for dark areas, and in comparison with this the present invention has the advantage that the number of secondary electrons available for generating picture signals is a minimum for dark areas, so that noise should be a minimum for those areas.

In order that the said invention may be clearly understood and readily carried into effect, the same will now be more fully described with reference to the accompanying drawing wherein a television transmission tube according to one example of the present invention is illustrated.

Referring to the drawing, the tube comprises a highly evacuated glass envelope 1 with a flat glass window 2 at one end. On the inner surface of the glass window there is provided a semi-transparent conducting photo-cathode 3 formed for example of an antimony-caesium layer, a lens system indicated at 4 being arranged to focus an optical image of the object for transmission onto the photo-cathode 3 and so liberate photo-electrons therefrom. An anode 5 which may be a metallic coating on the tube wall, is maintained at a potential of about 50 volts positive with respect to the photo-cathode 3 which is at earth potential in this example, so that an axial electrostatic field is set up between the photo-cathode 3 and the anode 5 which accelerates the electrons liberated from the photo-cathode. A ring electrode 6 is disposed between the anode 5 and the target electrode 7 of the tube, and is maintained at or near earth potential so that it decelerates the photo-electrons as they approach the target electrode 7 and an axial magnetic field established by current in a solenoid 10 brings the electrons to a focus on the target electrode 7.

The target electrode 7 may comprise a very

thin sheet of glass about 0.0001 inch thick and of such a specific resistance that with these dimensions the resistance between opposite points on its two surfaces is relatively small but between two neighbouring picture points on its surface, it is large. Very close to the target electrode 7, but on the side opposite the photo-cathode 3, is mounted a metal mesh 8 of very fine pitch and of low shadow ratio, and maintained at a small positive potential (say 3 volts) relative to that of the photo-cathode.

At the end of the tube 1 opposite the photo-cathode 3, but off-set with reference to the tube axis is arranged an electron gun consisting of a thermionic cathode 11, a modulator electrode 12, and an anode 13, and on the application of the potentials indicated to the respective electrodes, an electron beam indicated at 15 is produced which emerges from the electron gun with a velocity corresponding approximately to 150 volts, coming immediately into the field of influence of the axial magnetic field produced by the solenoid 10 which, as shown, envelops the greater proportion of the length of the tube 1. The beam 15 then passes between two so-called lift plates 14 (only one of which is visible) which on the application of a suitable potential produce an electrostatic field which in conjunction with the axial magnetic field deflects the beam in known manner, so that it emerges from between the plates 14 at a point coincident with the axis of the tube. The beam then passes through a region where there is no electrostatic field, the region being surrounded by a wall anode 9 which is maintained at the same potential as the anode 13, and in this region the beam is subjected to two transverse magnetic fields at right angles to one another and produced by two pairs of saddle coils, one pair 16 of which is shown. These transverse magnetic fields are arranged to cause the line and frame scanning deflections of the beam 15, in known manner, and on leaving the influence of these fields, since it is still subjected to the axial magnetic field of the coil 10, the beam travels parallel to the axis of the tube towards the surface of the target electrode 7. However, on approaching the target electrode, the beam enters a decelerating electrostatic field between a cylindrical wall anode 9 and the metal mesh 8. Electrons which return from the target follow approximately the path of the incident electron beam 15 until they reach the lift plates 14, where they are deflected in the opposite sense from the incident beam and enter an electron multiplier indicated at 17 and comprising a number of multiplying grids and a collecting electrode which in operation are maintained at the potentials indicated. The output of the multiplier forms the signal output of the tube and it is fed to the input of an amplifier which may be of conventional design and is not shown.

In operation of the tube, the photo-electrons liberated by the photo-cathode 3 are focussed as an electron image on the target electrode 7 at such a low velocity that the photo-electrons liberate very few secondary electrons from the target electrode and hence elemental areas of the glass surface facing the photocathode 3 are charged negatively in proportion to the brightness of the elementary areas of the optical image, and hence of the object for transmission. These negative charges at first induce equal negative charges on the opposite surface of the target electrode 7 and then leak through the glass to equalise the potential across the thickness of the glass. The

time constant of the small condensers constituted by the elemental areas of the target electrode must be smaller than the frame-scan period and no appreciable leakage must occur along the surfaces of the target electrode.

The scanning electron beam reaches the target electrode 7 through the interstices of the mesh 8, with a velocity corresponding to about 100 volts, sufficient to liberate more than one secondary electron from the glass surface for each primary electron incident thereon. Provided the scanned surface of the target electrode 7 is at a potential negative with respect to the mesh 8, these secondary electrons are accelerated towards the mesh, some being captured by it, but most of them pass through and enter the field between the mesh 8 and the anode 9 and are directed to the electron multiplier 17. This removal of secondary electrons from the target electrode 7 continues until the potential of the scanned surface of the target electrode equals or slightly exceeds the potential of the mesh 8 when there is no field to accelerate the secondary electrons through the mesh and a condition of equilibrium is reached when the beam of secondary electrons directed to the electron multiplier equals the incident scanning beam. Therefore if there is no light falling on the photocathode 3 and hence no electron image focussed on the target electrode 7, the latter electrode will attain an equilibrium potential approximately equal to the potential of the metal mesh. However when an electron image of the object for transmission is focussed on the target electrode, elemental areas thereof are, as stated, charged negatively in proportion to the brightness of the elemental areas of the object, and hence when the target is scanned secondary electrons are accelerated through the mesh 8 from the elemental areas of the target electrode, the number of secondary electrons being proportional to the brightness of the respective elemental areas of the object. Therefore more secondary electrons are accelerated through the mesh 8 and directed to the electron multiplier 17 from elemental areas of the target electrode corresponding to the bright areas of the object for transmission, and as previously indicated the maximum input to the electron multiplier corresponds to picture white and the minimum input corresponds to picture black. In addition the number of secondary electrons accelerated through the mesh 8 is not dependent upon variations in the secondary number of emissions from said target electrode since the return beam of electrons is controlled by the mesh 8 and the potentials of the target electrode 7, which are brought to the same relative potential at each scan of the target electrode, irrespective of variations in secondary emission. The mesh 8 may therefore be regarded as a control electrode. The potential of the mesh 8 is arranged to be adjustable over a small range to compensate for variations at the potential source.

The capacity which is charged by the photo-electrons and discharged by the electron beam 15 is that between the target electrode 7 and the mesh 8 in the example illustrated. Hence to obtain a sufficient charge storage the mesh 8 must be disposed very close to the target electrode 7 and the potential swing of the target electrode must be as large as possible, for example about 2 volts swing. However, if it is necessary to obtain greater charge storage, the target electrode 7 may be replaced by a double

sided mosaic screen of the type in which an insulated metal mesh has its interstices filled with conducting plugs. The capacity of the plugs, constituting the elements of the mosaic screen, to the mesh core would then be much greater than between the target electrode and the mesh 8 so that the charges stored would be correspondingly greater, the capacity between the mesh 8 and the double sided mosaic screen being then of secondary importance so that the potential variations could be reduced.

The potential to which an elemental area of the mosaic screen may be charged is determined by the potentials of the photo-cathode 3 and of the mesh 8, and within limits can be increased or decreased by varying the potential of the mesh 8. In the white or high light areas of the image the capacity of the corresponding elemental areas of the target electrode may become fully charged, excess photo-electrons being reflected in that case and returned to the photo-cathode 3. Thus the signal/light characteristic may be approximately linear in the low light areas turning gradually to a saturated portion in the high light areas, which would be suitable for television transmission. If the potential range on the target electrode during transmission is too great, pulling of the incident photo-electrons laterally may occur in the areas corresponding to white. This may however be avoided by using a high capacity double sided mosaic screen such as referred to above, or by using a grid close to the target electrode 7 at the side thereof facing the photo-cathode 3.

In accordance with a modification of the invention, which may result in obtaining a still further improved signal-noise ratio, means may be provided for controlling the secondary electrons which pass the metal mesh 8 in dependence upon the velocity of said secondary electrons, whereby secondary electrons liberated from uncharged areas of the target electrode by the incident beam 15 are prevented from reaching the electron multiplier 17. It will be appreciated that secondary electrons liberated from the charged areas of the target electrode 7 will have a higher average velocity than those originating from uncharged areas, said average velocity being a maximum for areas corresponding to white. The velocity control may be effected by means of a grid 18 arranged in front of the electron multiplier 17 maintained at such potential as to turn back from the multiplier those secondary electrons liberated from uncharged areas of the target electrode 7 and admit those from charged areas, the grid 18 constituting in effect means for establishing a potential barrier to electrons liberated from uncharged areas. Thus the noise may be reduced in both the low light and high light areas.

Further modifications may of course be made to the embodiment of the present invention which is illustrated; for example the photo-cathode 3 and target electrode 7 may be constructed in very close proximity. The electrodes 5 and 6 are in that case unnecessary, and the definition of the electron image on the target electrode 7 is determined by the lateral spread of photo-electrons. If the two electrodes 3 and 7 are sufficiently close, adequate definition may be obtained in this way and the length of the tube may be appreciably decreased.

What I claim is:

1. A circuit arrangement for generating electrical signals corresponding to a light image, in-

cluding a pick-up tube having an evacuated envelope enclosing a target, elemental areas of which are capable of being charged to different potentials, a photoelectric cathode in said envelope for converting a light image into an electron image, circuit connections to cause said electron image to be projected on to said target with a velocity to form a negative charge image on said target, means for scanning said target with an electron beam having a velocity predetermined to release secondary electrons from said target, an electron pervious control electrode disposed before the scanned side of said target, means polarizing said control electrode to accelerate said secondary electrons through said control electrode in numbers dependent upon the negative potential of the respective elemental areas of said target, and signal generating means responsive to secondary electrons accelerated through said control electrode for generating electrical signals representative of the potential distribution on the elemental areas of said target with an increase in the number of electrons accelerated through said control electrode corresponding to an increase in the intensity of the light image.

2. Apparatus for generating electrical signals corresponding to a light image, including a pick-up tube having an evacuated envelope enclosing a target, elemental areas of which are capable of being charged to different potentials, means including a photoelectric cathode in said envelope for converting a light image to a negative charge image on said target, means for scanning said target with an electron beam having a velocity predetermined to release secondary electrons from said target, an electron pervious control electrode disposed before the scanned side of said target and polarized to accelerate said secondary electrons through said control electrode in numbers dependent upon the negative potential of the respective elemental areas of said target, signal generating means responsive to secondary electrons accelerated through said control electrode for generating electrical signals representative of the potential distribution on the elemental areas of said target with an increase in the number of electrons accelerated through said control electrode corresponding to an increase in the intensity of the light image, and an electron pervious electrode disposed between said control electrode and said signal generating means polarized to stop secondary electrons released from uncharged areas of said target before said secondary electrons reach said signal generating means.

3. A circuit arrangement for generating electrical signals corresponding to a light image, including a pick-up tube having an evacuated envelope enclosing a target, elemental areas of which are capable of being charged to different potentials, means including a photoelectric cathode in said envelope for converting a light image to an electron image, circuit connections to cause said electron image to be projected on to said target with a velocity to form a negative charge image on said target, means for scanning said target with an electron beam having a velocity predetermined to release secondary electrons from said target, an electron pervious control electrode disposed before the scanned side of said target, means polarizing said control electrode to accelerate said secondary electrons through said control electrode in numbers dependent upon the negative potential of the re-

spective elemental areas of said target with an increase in the number of electrons accelerated through said control electrode corresponding to an increase in the intensity of the light image, signal generating means, and means including a further control electrode polarized to a pre-determined potential for directing to said signal generating means all secondary electrons accelerated through said control electrode with velocities exceeding a minimum related to said pre-determined potential.
